(57) **CLAIM**

The ornamental design for a communication apparatus, as shown and described.

DESCRIPTION

FIG. 1 is a top, front prospective view of the communication apparatus;

FIG. 2 is a right-side elevational view thereof;

FIG. 3 is a top plan view thereof;

FIG. 4 is a front elevational view thereof;

FIG. 5 is a rear elevational view thereof;

FIG. 6 is a left-side elevational view thereof;

FIG. 7 is a bottom plan view thereof; and,

FIG. 8 is a top, rear perspective view thereof.

The broken lines immediately adjacent the shaded areas represent the bounds of the claimed design while all other broken lines are directed to environment and are for illustrative purposes only; the broken lines form no part of the claimed design.
